HOSIERY BOARD

Francis M. Southerland, Mebane, N. C.

Application October 22, 1952, Serial No. 316,137

3 Claims. (Cl. 223—76)

1

This invention relates to a fabric finishing apparatus, and more particularly to a structure employed for drying, finishing, setting and shaping hosiery or the like.

Commercial hosiery manufacturing consists of the knitting of the hosiery, after which the hosiery must be dyed and pressed to shape so as to be free from any creases or wrinkles in order to be readily marketable. The pressing treatment, known as boarding in the art, usually employs the use of a board or shaping structure conforming in shape to the desired finished article. In practice, the hose is placed over the board and the hose and its board are thereafter placed in a drying room, steam chest or autoclave for the necessary treatment, after which the hosiery and its board are removed and the hosiery is thereafter stripped from the board. Synthetic fibers are now being used extensively in the hosiery trade, and it frequently becomes necessary or desirable to shape or pre-set the hosiery after it leaves the knitting machines prior to dyeing or other treatments. The pre-setting of hosiery formed of synthetic fibers is commonly known in the art as pre-boarding.

The present invention is directed to an apparatus useful in either boarding or pre-boarding hosiery and is particularly adapted to the general type of boarding or pre-boarding machines disclosed in Oswald et al. patent, No. 2,351,063. In this type of machine, a plurality or bank of boards, either 24 or 48, depending upon the size of the machine, are mounted upon a common shaft so that the individual boards may be pivoted and rocked into a plurality of positions. Thus, when hosiery is to be placed upon a board, the latter is rocked about its support to a convenient position for the operator so that a hose may be placed over the board. Thereafter, the "loaded" board is rocked to a different position and a second board is rocked to the loading position. After all 24 or 48 boards are "loaded," the apparatus supporting the same is placed into a treating chamber, such as a drying chest, steam chest, autoclave or the like, depending upon the kind of treatment desired. Of course, after the necessary treatment has taken place, the supporting apparatus is removed from the treating chamber and the individual boards rock to a position convenient for the operator to strip the hose.

As the boards commonly used in the aforementioned apparatus are formed of metal and are usually cast, such boards are quite heavy and quite expensive to manufacture. In the normal boarding and pre-boarding operations, it

2

is necessary to have a bank of boards for each particular size of hose to be treated as well as for each particular type of hose. For instance, ankle socks of a given size would require a particular shape of board, while longer socks of the same foot size would require a different shape of board. Of course, ladies' hosiery, for the same given foot size aforementioned, would require a still different shape of board. Also, the various types of knitted hose require still different shapes of boards, and the size and shape of boards suitable for each particular class of hose varies with the foot size. Accordingly, when one multiplies the different sizes and shapes of boards necessary to properly take care of a hosiery mill by 24 or 48, depending upon the size of apparatus used, the number of individual boards required becomes exceedingly great. The cost of procuring a given number of boards of all of the various sizes and shapes is exceedingly high, and even the storage of the same when not in use creates a considerable problem.

In the type of apparatus as disclosed in the Oswald et al. patent aforementioned, the boards are provided with holes or yokes adjacent their bases for mounting upon their shaft and normally are provided with U-shaped openings terminating in a hook shaped portion for actuating mechanism to rock the board about its supporting shaft. Also, arcuate ribs are cast into the lower portion of the board, the ribs acting as spacers for the boards, thus preventing any frictional contact between the hosiery placed on adjacent boards.

When a different size, shape or type of hosiery is to be boarded or pre-boarded from that previously boarded or pre-boarded, it becomes necessary to remove the entire bank of boards and their actuating mechanism and replace the same with another bank of boards of the desired shape and size.

The present invention has been perfected in an effort to obviate a number of the problems of the prior art. Thus, the prime object of the present invention is to reduce the cost and storage space required for each bank of various shapes and sizes of boards.

Another object of the invention is to reduce the time previously required in changing a bank of boards.

Other objects of the invention will be obvious to those skilled in the art from an understanding of the invention as disclosed in the following specification with the accompanying drawings, in which:

Figure 1 is a side view of the invention;

Figure 2 is a sectional view taken on line 2—2 of Figure 1;

Figure 3 is a sectional view taken on line 3—3 of Figure 2; and

Figure 4 is an enlarged perspective view of 5 the invention.

The board normally used in the Oswald et al. apparatus somewhat resembles the structure shown in Figure 1, except that the upper shaping portion of the board, i. e., the portion upon which the hose is placed, is formed integrally with the lower or base portion. The lower or base portion is provided with a yoke 10 which is adapted to be secured to a shaft, not shown. The shank 11 extends upwardly from the yoke and is shaped 15 to provide an arcuate section 12, the latter terminating in a hook-like portion 13. An arcuately shaped spacing rib 14 extends outwardly from the section 12. The base terminates in a substantially rectangular portion in cross section as 20 indicated at 16. It will be understood, of course, that a bank of the aforementioned structure, usually consisting of 24 or 48 individual bases, is mounted in its supporting structure which normally comprises a shaft about which the yoke 10 extends and suitable operating mechanism is secured to the hook 13, etc. so that the bases may be rocked from one operating position to another. As the bases are mounted in close proximity to each other, it is necessary to provide 30 a spacing means therefor, such as the arcuate rib 14, to prevent any frictional contact between the hose placed upon the boards. All of the aforementioned structure is commonly used with the type of apparatus generally disclosed in the aforementioned patent to Oswald et al. The boards used in the Oswald et al. type of apparatus extended upwardly from the base 16 and were shaped according to the desired shape of the 35 hosiery to be treated, the entire board being cast 40 into one integral structure.

The present invention is designed to have the shaping portion of the board detachable from its base, which is evident from the drawings. This function is accomplished by forming a rectangular groove of considerable depth and thickness in the base portion 16, the groove being indicated by reference numeral 20. One face of the portion 16 overlying the groove 20 is cut away to form a U-shaped opening 22. The shaping portion of the board 25 is provided, at its lower edge, with an elongated slot 26. The inner face of the base forming the groove has a bolt 30 welded or otherwise fixedly secured thereto, the bolt 30 being adapted to receive the slot 26 of the shaping portion of the board 25, as illustrated. A suitable washer 31 and nut 32 are provided to lock the forming portion 25 to the base 16, as shown in Figure 1.

It should be noted that the groove 20 is provided with substantially straight side walls 40, as indicated in dotted lines in Figure 1; and that the thickness of the groove 20, as more clearly shown in Figure 3, is considerably greater than the thickness of the shaping portion of the board 25. It will also be noted in Figures 1 and 3 that the lower portion of the shaping board 25 is of less width than the width of the groove 20, thereby enabling easy replacement of the forming board 25.

The bolt 30 does not extend through the base, thus preventing a flush side to the base and that the bolt does not extend beyond the outer surface of the opposite side of the base. The groove 20 is of sufficient depth or thickness to accom-

modate the base extremity of the forming member 25, together with the washer and nut so that the nut and its bolt do not extend beyond the face of the base 16. Thus, there are no parts of the attaching means for the shaping member which extend beyond the outer coplaner surfaces of the base 16, which is of importance. As previously mentioned, the bases are positioned on a common shaft in close proximity to each other, the spacing rib 14 of one base usually contacting the opposite side of another base. Should any portion of the shaping member attaching means extend any distance beyond the forces of the base, the bases could not be rocked relative to each other.

It will be understood, of course, that the hosiery mill utilizing the type of apparatus generally disclosed in the aforementioned Oswald patent will have a bank, either 24 or 48 as the case may be, of forming or shaping boards 25, one bank for each particular type or size of hosiery to be boarded or pre-boarded. Upon the assumption that, after hosiery of a given type or size has been treated on the apparatus, it is desired to board or pre-board a different type or size of hosiery, all that an operator need do is to pivot the first outward board about the supporting shaft, loosen the nut 32 and thereafter remove the shaping portion of the board 25 from its base. A different size or form of shaping board having a similar slot, as indicated at 26, is then placed in the groove 20 so that the bolt 30 extends through the slot 26 and the nut 32 again tightened. This operation is repeated until the entire bank of forming boards have been changed. By such procedure it becomes unnecessary to remove the entire base and release the operating mechanism secured thereto as would be the case if the board was formed of one integral cast member. As the side walls 40 forming the groove 20 are substantially straight and parallel with the side walls of the lower portion of the forming board 25, the forming board 25 is incapable of any appreciable rocking about the bolt 30.

It will be obvious that while the lower base portion of the board is preferably cast so as to be capable of withstanding the necessary shocks imparted thereto, the upper shaping portion of the board may be formed of sheet metal, such as aluminum or aluminum alloy. By being able to construct the shaping portion of the board of light weight metal and in generally sheet form, storage and transportation from storage to use is far more convenient than present day practices of having to store a large number of banks of integrally cast boards with bases. Furthermore, the forming portion of the boards may be made of metal which will quickly absorb and dissipate heat, thereby reducing the treating time of the hosiery. Also, it will be obvious that the cast of an extremely large number of shaping boards per se with a single set or bank of bases is considerably less than the same number of boards having integral bases.

I claim:

1. A hosiery board comprising, in combination, a base having opposed faces and end walls and shaft attaching means, a groove formed in the upper portion of said base positioned inwardly of the side walls, a detachable hosiery shaping member capable of having an inwardly extending extremity complementary in size and shape to said groove positioned within said groove, the inner face of one side of said base forming said groove having a bolt fixedly secured thereto and extending outwardly from said face, the oppo-

site face of the side of said base forming said groove having a cut-away portion opposite said bolt extending from the top of said groove downwardly beyond said bolt and providing a substantial space around the periphery thereof to expose the same, said shaping member having a slot therein extending upwardly from the bottom thereof to receive said bolt, and a nut capable of threadedly engaging said bolt for detachably securing said shaping member to said base.

2. A hosiery board comprising, in combination, a base having opposed faces and end walls and shaft attaching means, a rectangularly shaped groove in cross section formed in the upper portion of said base positioned inwardly of the end walls, a detachable hosiery shaping member capable of having an inwardly extending extremity complementary shaped in cross section to said groove positioned within said groove, the inner face of one side of said base forming said groove having a bolt fixedly secured thereto and the opposite face of the side of said base having a

15

10

cut-away portion opposite said bolt extending from the top of said groove downwardly beyond said bolt and providing a substantial space around the periphery thereof to expose the same, said shaping member having a slot therein extending upwardly from the bottom thereof to receive said bolt, said bolt terminating short of the outer face of said side having the cut-away portion therein, a nut capable of threadedly engaging said bolt, the thickness of said groove being sufficient to accommodate said shaping member and nut so that the latter does not extend beyond the face of said base.
